UNITED STATES PATENT OFFICE.

JOHN D. WILSON, OF GREENLEAF, KANSAS.

TETHER.

SPECIFICATION forming part of Letters Patent No. 340,649, dated April 27, 1886.

Application filed December 4, 1885. Serial No. 184,743. (No model.)

To all whom it may concern:

Be it known that I, JOHN D. WILSON, a citizen of the United States, residing at Greenleaf, in the county of Washington and State of 5 Kansas, have invented a new and useful Improvement in Tethers, of which the following is a specification, reference being had to the accompanying drawings.

My invention relates to tethers; and it consists of the peculiar construction, combination, and arrangement of parts, substantially as hereinafter fully set forth and claimed.

One of the objects of this invention is to provide an improved tether for confining domestic animals within certain limits, while at 15 the same time they are allowed to move and feed freely within the tether.

A further object of my invention is to provide means for catching and retaining the 20 animal or animals when it or they attempt to escape; to provide an improved anchor or hopple which shall not injure the animal to which the hopple is attached when it attempts to escape or while feeding, and, further, to 25 provide means which shall be very simple, strong, and durable in construction, and thoroughly effective for the purpose designed.

In the accompanying drawings, Figure 1 is a view showing the manner of applying and 30 using the device. Figs. 2 and 3 are detail views of the corner-post bracket or plate. Fig. 4 is a detail view of the casting for the intermediate posts, and Fig. 5 is a detail view of the animal hopple or anchor.

35 Referring to the drawings, in which like letters of reference indicate corresponding parts in all the figures, A. designates the corner-posts of the inclosure; B, the intermediate posts, and C C' the wires passed through 40 guide-plates therefor, secured to the said corner and intermediate posts, and having their ends secured to stakes C², arranged at proper distances from the corner-post, as clearly shown in Fig. 1 of the drawings.

45 D designates the guide-plates or castings, having sockets for the crossing wires of the inclosure and secured to the corner-posts A thereof. This corner-post guide plate or casting D is preferably made triangular in form, 50 and projecting outwardly from the post A on

the inner side of the inclosure, and said plate has depending slotted lugs d at two of its angles or corners, and the other angle or corner is perforated, as at d', for the passage of screws or bolts to secure the device to the corner-post. 55 The wires C C' pass through the slotted flanges of the plate or casting at right angles to each other, and are held therein, and said wires are secured at their ends to the exterior stakes, C².

E designates the guide or casting for the intermediate posts, B, which comprises two right-angled arms, e e', to be secured to the upper angle of said posts by means of screws or bolts, and having an inwardly-projecting arm, e², having an eye or opening, e³, through 60 which passes one of the wires of the inclosure.

F designates the hopple or anchor, which consists of a plank or weight, f, a casting, F', secured thereto, a rod, f', journaled at one end in the casting, and a chain, rope, or other 65 flexible connection between an eye of the said rod and the fore leg or the head of the animal. The casting F' has two perforated lugs, g g', arranged at its end and near the middle, on one surface thereof, and on its other face it has 70 a projecting lug, h, which fits against the weight f. The casting F' is bent at its middle, so as to have one end thereof project beyond the weight at an angle thereto, and said casting is secured to the weight by a screw or bolt. 75 One end of the rod f' has an enlarged head, which bears against the lug g' of the casting, and the other end of said rod has an eye to 80 which the chain is connected.

It will be observed that when an animal has 85 leaped over one of the wires C C' of the inclosure, the weight f of the hopper or anchor will catch on the wire and prevent its further escape, and if the animal attempts to drag the weight lengthwise of the wire the inwardly-projecting brackets, guides, or castings D E 90 will prevent the said weight from coming in contact with the posts A B and injuring the same.

Having thus fully described my invention, 95 what I claim as new, and desire to secure by Letters Patent, is—

1. The herein-described anchor or hopple, consisting of a weight, a casting secured thereon, a rod journaled so as to rotate in the cast- 100

ing and free to move longitudinally therein, and a rope or chain connected to the rod, substantially as described.

2. The herein-described tether, comprising 5 corner-posts having angular plates D, secured thereto, and provided with guides arranged at an angle to each other, the intermediate posts having castings E, and the stakes C², in combination with the wires loosely mounted in

the guides and castings, substantially as described.

In testimony that I claim the foregoing as my own I have hereto affixed my signature in presence of two witnesses.

JOHN D. WILSON.
